UNITED STATES PATENT OFFICE

2,610,388

MACHINE FOR OPERATING ON STRIP STOCK

Frederick Koch, Sparta, N. J., assignor to C. Todd,
Rutherford, N. J., as trustee

Application August 18, 1950, Serial No. 180,131

1 Claim. (Cl. 29—33)

1

The invention disclosed in this patent application concerns certain improvements in so-called "Multi-Slide" machines.

Machines known under this name are characterized by having a bed supporting various machine tool elements operated by cams and eccentrics on shafts geared together about the bed, substantially as shown in Borton Patent 1,883,513 of October 18, 1932.

Basically these machine tools are punch press devices mounted in properly cooperating relation on the bed and actuated in properly synchronized order by the cams and eccentrics on the surrounding shafts.

With such an organization it has been possible to perform a great variety of piercing, punching, blanking, forming, swaging, drawing, riveting, staking, bending, cutting and assembling operations.

Some limitations have developed, however, and it is with a view to overcoming those limitations that the present invention has been devised.

Following basic principles of press operation, "Multi-Slide" machines have been built with press units made up of companion ram and bolster elements carrying the necessary die sets. The rams have been mounted on the front of the bed so as to be operated by the front cam shaft, and the bolsters at the back, braced to take the load by an upstanding abutment rail extending along the rear edge of the bed.

With this arrangement operations are directed toward the back of the strip so that bending and forming will be to that side of the strip and any burrs will be left at the back and scrap be knocked out at the back of the strip.

While these limiting factors ordinarily are not objectionable, there are occasions where it would be highly desirable to work in from the back of the strip or possibly to simultaneously work in from both sides of the strip.

Accordingly, it is a general purpose of the present invention to so revise and re-design these "Multi-Slide" machines that they may operate with equal facility on either or both sides of the stock which they handle and to accomplish this in a manner and with structure utilizing the best principles of this machine.

More specific objects of the invention are to simplify, stiffen and strengthen the bed structure and to so arrange the parts that they may be quickly and easily mounted on the bed to operate from either the front or the back of the machine; to provide a symmetrical form of structure and to accomplish an equalizing and balancing of

2

power as applied by the shafts at the different sides of the machine.

A special important object of the invention is to enable the production of more complicated or more extensively worked pieces than has heretofore been possible on these machines, for example, to effect deeper drawing or longer or more varied bending operations.

Other special objects and the novel features of invention through which all such purposes are attained are set forth or will appear in the course of the following specification.

The drawings accompanying and forming part of the specification are illustrative of a present commercial embodiment of the invention. Structure, however, may be modified and changed, all within the true intent and broad scope of the invention as hereinafter defined and claimed.

Fig. 1 in the drawings is a general top plan view of one of the new "Multi-Slide" machines having the center stock line feed feature of the present invention;

Fig. 2 is a broken transverse cross sectional view of the bed of the machine as on substantially the plane of line 2—2 of Fig. 1;

Fig. 3 is an enlarged broken cross sectional view of the machine as on substantially the plane of line 3—3 of Fig. 1, showing a ram operating from the back of the machine;

Fig. 4 is a similar view on substantially the plane of line 4—4 of Fig. 1, showing companion rams simultaneously operating from both sides of the machine.

In the present invention the stock is fed in on a center line 5 over the bed 6 and the latter, as shown in Fig. 2, is flat and substantially symmetrical with plain, flat sides 7 and 8 and with undercut anchorage slots 9 and 10 in the top at equal distances from the center line 5. The center groove 11 is suitably shaped to accommodate slides which may be operated in from one or both ends of the machine.

The bed carries, at the four corners, journal bearings 12 for the front and back shafts 13, 14, and end shafts 15, 16, connected at adjoining ends by gears in the gear boxes 17. Power is applied to this ring of shafting usually through gearing to shaft 15.

Fig. 1 illustrates a special tooling arrangement in which two rams are operated from the front shaft and two from the back shaft and with intermediate rams directly opposite and directly cooperating.

The front rams are designated 18 and 19 and the back rams 20 and 21.

These rams in each instance are slidably mounted on a base 22 resting on the bed and having a key strip 23 interlockingly engaged in one of the anchorage grooves 9 or 10. Bolts 24 engaged with nuts 25 in the undercut portions of these grooves secure the bases in firmly interlocked engagement on the bed.

Bolsters or back plates 26, 27, are mounted on the bed in cooperating relation with the front and back rams 18, 21, these having keys 28 corresponding to the keys 23 of the ram bases and bolts and nuts 24, 25, by which they may be secured down on the bed in the same manner as the ram bases.

The intermediate rams 19, 20, are shown as similarly secured, Fig. 4, directly opposite so as to effect drawing, bending, forming or other operations possibly double the extent that might be accomplished with a single ram.

In this coacting relation of the two rams they may be timed so as to one operate in advance of or simultaneously with the other and so as at the end of the cycle, to leave the stock substantially in the center line, requiring no stripper action to separate the stock from the dies.

The cams for actuating the ram slides are indicated at 29, 30, 31, 32, these being designed to effectuate desired timing and operation of the rockers 33, 34, 35, 36, linked by toggles 37, 38, 39, 40, with the respective slides. These cams may be of the split construction used on "Multi-Slide" machines, in accordance with Borton Patent 2,161,243 of June 6, 1939, and which by reason of such split construction may be readily changed from one shaft to the other.

The rams and bolsters are tied together in fixed relation over the bed by tie bars or bridges designated 41, 42, 43, the bars 41 and 43 connecting the ram bases and companion bolsters, and the bar 42 connecting opposing ram bases.

In all instances, therefore, the companion press members are locked together in fixed relationship.

In the case of the opposed rams the loads may be equally or substantially equally balanced and in other instances the loads on the cam shafts at opposite sides of the machine may be substantially balanced. The power applied by the shafts may thus be more or less equally distributed about the bed to create free, smooth running operating conditions without undue loading at any particular point. This distribution of power enables faster operation and hence higher production.

The complete interchangeability of ram and bolster bases on the bed enables the machine to be quickly set up for accomplishing greater variety of operations and greater extent of movement for bending, forming, embossing, or the like.

The bed being of substantially symmetrical design, can be produced at lower cost and be actually stronger, at no greater and possibly less weight. The stock, advanced over the center of the bed, may be worked both ways or, if need be, worked to double the extent to one side. Burrs may be located either to one or to both sides, and the same as to any scrap that may be struck out of the strip. Stampings of more or less complicated form may be produced by working the stock alternately from opposite sides or simultaneously by rams coacting from opposite sides of the machine.

The many advantages attained by this invention do not interfere in any way with the operations which may be performed about the stripper plunger 44, Fig. 1, by means of the cooperating former slides 45, 46, 47, 48.

What is claimed is:

A metal working machine for operating on straight lengths of strip stock, comprising a machine tool bed substantially symmetrical to opposite sides of a central longitudinal straight stock feed line, said bed being substantially flat on top and having corresponding substantially straight, flat, parallel longitudinal sides spaced the same distance from said central stock feed line and having corresponding parallel, longitudinal ram positioning grooves in the top of the same spaced the same distance to opposite sides of said central feed line, parallel cam shafts journaled at opposite sides of said bed and spaced the same distance to opposite sides of said central feed line, said shafts being located in the same relation with respect to the top of the bed and with respect to the sides of the bed and geared to rotate in unison, opposed rams at opposite sides 15 of the stock feed line and operating in opposite directions against opposite sides of the stock, said oppositely acting rams having bases removably mounted on the bed in longitudinally adjustable relation at opposite sides of the central stock feed line, keys on said ram bases engaged in said positioning grooves in the bed, means for removably securing said ram bases keyed on the bed in the opposing relation described at different positions in the length of the bed, said ram bases being reversible end-for-end and interchangeably mountable on the bed on opposite sides of the central stock feed line, whereby either ram may be used at either side of the stock feed line and the stock be maintained in substantially a straight line, 30 and cams for operating said rams interchangeably engageable on said cam shafts for actuating said rams in cooperative timed relation, mounted as described at either side of said central straight stock feed line.
